CLAIM

The ornamental design of a lid of a vaporizer, substantially as shown and described.

DESCRIPTION

FIG. 1 is a top isometric view of a lid of a vaporizer in accordance with the present invention.

FIG. 2 is a bottom isometric view of the lid of the vaporizer of FIG. 1.

FIG. 3 is a front view thereof. The back view the lid of FIG. 1 is identical to the right side view and is therefore omitted. FIG. 4 is a right side view thereof. The left side view the lid of FIG. 1 is identical to the right side view and is therefore omitted.

FIG. 5 is a top view thereof.

FIG. 6 is a bottom view thereof; and,

FIG. 7 is a front isometric view of a lid of a vaporizer shown in an open state of use with a vaporizer.

The broken lines shown are for illustrative purposes only. None of the broken lines form a part of the claimed design. For example, in FIG. 7 the dashed broken lines illustrate elements (including environmental structures) such as a vaporization device that forms no part of the claimed design.
